UNITED STATES PATENT OFFICE.

CHARLES L. PHILLIPS, OF AUBURN, NEW YORK.

GUNNER'S REPLOTTING APPARATUS.

SPECIFICATION forming part of Letters Patent No. 674,517, dated May 21, 1901.

Application filed August 28, 1900. Serial No. 28,301. (No model.)

To all whom it may concern:

Be it known that I, CHARLES L. PHILLIPS, a citizen of the United States, and a resident of Auburn, in the county of Cayuga and State 5 of New York, (having my present post-office address at Fort Hancock, Sandy Hook, New Jersey,) have invented a Gunner's Replotting Apparatus, of which the following is a specification, reference being had to the accompanying drawings, in which—

Figure 1 illustrates the table of the apparatus, shown in plan, with the protractor-scale in position upon it. Fig. 2 illustrates, likewise in plan, one of my "concentric-circle" 15 sheets. Fig. 3 illustrates a plan view of the parts in position for operation. Fig. 4 illustrates an edge-wise elevation of the apparatus, partly broken away in its medial section.

The object of my invention is to provide an 20 inexpensive, quickly-operative, easily-transported, and practical apparatus for determining the distance and direction of any object, stationary or movable—for instance, an enemy's fort, gun-boat, or other target—from a 25 given point—as, for instance, the gun which is to be trained upon such object—when the direction and distance of both from another given point—i. e., a range-finder—are known.

My invention has special application to the 30 service of sea-coast guns in the determination of ranges based upon distance and position data furnished by the observations of a range-finder. The operation of a range-finder and the data furnished by it are too well known 35 to require description here.

As constructed and adjusted for use the apparatus consists of a table or board A, (which may beneficially be substantially semicircular, as shown, although it may be 40 of any other preferred form,) having upon the outer edge of its upper surface a diagonal protractor-scale B, conveniently subdivided and marked, so as to read degrees of arc, and an arm C, pivoted at the center of 45 the protractor-scale, as at D, which is also conveniently subdivided and numbered along its fiducial edge, as at E, from the pivot outward to a point distant from its outer end not less than the width of the protractor-scale, where- 50 by it is adapted to indicate distances according to any determined scale in a manner well known. Where the fiducial edge of the arm

crosses the protractor-scale, as seen in the drawings, it is suitably subdivided, as at F, to allow the reading of minutes of arc. The 55 space on the surface of the board or table lying within the protractor-scale is occupied by a series of concentric circles G G G, &c., which are produced upon a separate sheet of paper G or upon equivalent material, as shown in 60 Fig. 2. The circles are spaced equidistantly and are numbered as may be convenient to read distances, according to the determined scale from the common center of the concentric circles. In the illustration shown (see 65 Fig. 4) the distances indicated commence with "2000" and increase outwardly by steps of five hundred. These figures in the present case indicate lineal yards; but they may indicate any other preferred distance. On 70 the actual sheets I usually indicate the increments in distance from the center outwardly by other lines indicating one hundred yards, or sometimes fifty yards; but for simplification of the drawings these minor subdivisions 75 have been omitted. The subdivisions may be such as preferred. As thus constructed and adjusted the center of the pivot D represents the position of the range-finder, and the center of the concentric circles indicates 80 the position of the gun. The distance-arm C being placed so that, as determined by the protractor-scale, its fiducial edge has the direction of the target from the range-finder, the subdivisions of the arm, reading the distance of the target from the range-finder, will 85 fix the location of the target upon the board or table, and the reading of the concentric circle, or that one of its subdivisions which passes through this point, determines the distance or range of the target from the gun. The characteristic feature of this invention consists in this use of a series of concentric circles produced upon a separate sheet or 90 surface and adapted to be superposed and adjusted upon the board or table carrying the protractor-scale in such manner that the foregoing results can be attained.

To give a clearer understanding of the apparatus, its several parts will be described 100 somewhat more in detail, as follows:

First. The board or table A may be made of any suitable size, shape, and material. I prefer that it should be substantially semi-

circular, as shown, and ordinarily from three to four feet in diameter. The size, however, will be determined by the scale adopted and the maximum distance from the range-finder 5 to the target, and its shape will be determined by that of the protractor-scale. This board or table may be provided with legs, if desired; but for convenience of manipulation and transportation it is ordinarily better 10 to have it in the form of a board or tablet.

Second. The protractor-scale may be made of metal or other suitable material, which is fastened in any preferred manner to the surface of the board. It may conveniently be 15 merely printed upon a sheet of paper or other suitable material and pasted or otherwise attached to the surface of the board.

Third. The sheet of concentric circles, as shown in Fig. 2, is preferably a sheet of paper, which may be beneficially made waterproof. A sheet or plate of metal or any other suitable material upon which the series of 20 circles and the distance designations can be produced may be substituted for the paper.

Fourth. The distance arm or indicator, of metal or other suitable material, pivoted at the center of the protractor-scale and bearing subdivisions and other indicia, as above described, is preferably provided with a metallic plate H, (see Fig. 3,) adapted to be securely attached, as by screws I, to the board A, so as to give firm pivotal connection for the arm. The plate is not essential, however,

The assembling of these parts in the adjustment of the apparatus is as follows: First fasten the pivot-plate H to the board A so that the center of the pivot will be at the center of the protractor-scale. Next, if the protractor-scale is upon a sheet of paper or other 35 such material attach it to the board or table with glue or otherwise in such manner that its center is at the point to be occupied by the center of the pivot. If the protractor-scale is of metal, then it and the plate are 40 usually permanent parts of the board. Indeed, this may be the case if the protractor-scale be produced upon paper or similar material. Next number the graduations of the 45 protractor-scale, which are normally left unnumbered, in such manner as best suits the conditions under which the device is to be used—that is to say, locate the numerical designations of the degrees of arc relative to the range-finder as may be necessary owing 50 to the position of the gun and the extent of its field of fire, so that the sweep of the arm to determine the distance of the target from the gun may be within the range of the protractor-scale without running off the board.

60 Next attach the distance-arm C by its pivot D to the plate H and mark the point upon the table or board which, as determined by the numbering of the divisions of the protractor-scale and by the adopted scale of distances, 65 which is the scale of the arm, is in the direction and at the distance from the center of the pivot that the gun is from the range-finder,

and this point will be the position of the gun. Next adjust and fasten in any preferred manner the sheet of concentric circles G' upon the board or table in such manner that the common center of these circles will be at the point marked as the position of the gun, as last above explained, cutting away and removing all portions of the concentric-circle sheet that overlap the protractor-scale. The device is then ready for use, an illustration of which will be as follows, reference being had to Fig. 3 and to the dotted lines, &c., produced thereon: Assume that the gun, 70 relative to the range-finder, has the position azimuth α degrees and distance a yards and that the field of fire of the gun lies wholly or in great part upon the right of the line joining the range-finder and gun. Starting 75 with the board, protractor-scale, and arm assembled, but with the graduations of the protractor-scale still unnumbered, the conditions above assumed require that the center of the concentric circles shall be approximately at 90 K', whose azimuth from the range-finder is approximately α degrees and whose distance from the same point is approximately a yards. Move the distance-arm until its fiducial edge passes through the point thus approximately 80 determined and number the graduations of the protractor-scale lying nearest to the fiducial edge of the arm to read α (whole) degrees. The other graduations are then numbered 85 from this one increasingly in the direction of the movement of the hands of a watch. Set the arm so that the reading of the protractor-scale is the direction in degrees and minutes of the gun from the range-finder and mark upon the board the point K, which as determined by the reading of the arm-scale has 90 the distance of the gun from the range-finder. This point so marked determines the position of the common center of the concentric circles, and the sheet bearing these circles is 95 then attached to the board, as above described. Assume that the target as observed from the range-finder has the direction γ degrees and distance 9 is at the point M, Fig. 3. The distance, therefore, of this point M or the range 100 from the gun, as determined by the subdivision (in this case estimated) of the concentric circle passing through or near this point, is eight thousand eight hundred and seventy-five, approximately.

The use of the protractor-scale and the sheet or plate of concentric circles and the fact that the divisions of the protractor-scale are left unnumbered render it possible and convenient in the assembling and adjustment of the parts to adapt the device to the circumstances of distance and direction obtaining at any desired point of use.

It will be obvious to those who are familiar with this art that modifications may be made in the details of construction and adaptation of the parts without departing from the essentials of the invention. I therefore do not limit myself to such details.

Having described my invention, I claim—

1. In a replotting apparatus the combination of a table or board provided with a protractor-scale, a distance-arm pivoted thereto and subdivided according to any suitable scale and adapted to coact with said protractor-scale, and a sheet or plate carrying a series of concentric circles, which is spread upon the table and the center of which is adjustable relative to the center of the protractor-scale whereby it is adapted to coact with said scale and said arm, for the purposes set forth.
2. For use in conjunction with a protractor-scale and distance-arm, a sheet or plate of suitable material carrying a series of concentric circles spaced and numbered so as to indicate distance in accordance with the scale of the distance-arm, as set forth.
3. A replotting apparatus embodying a board or table, a protractor-scale produced thereon, a distance-arm concentrically pivoted to the board or table relative to the protractor-scale, a sheet or plate of suitable material which is spread upon the table and which is adjustable relative to the center of the protractor-scale and carrying a series of concentric circles, said circles being spaced and numbered to coincide with the scale of the said arm, for the purposes set forth.

Signed at New York, in the county of New York and State of New York, this 8th day of August, 1900.
